CLAIM

The ornamental design for a “front sight for a firearm,” as shown and described.

DESCRIPTION

FIG. 1 is a perspective view of a “front sight for a firearm,” showing my new design from above and the rear; FIG. 2 is a front elevational view thereof; FIG. 3 is a left side elevational view thereof, and the right side being a mirror image thereof; FIG. 4 is a rear elevational view thereof; FIG. 5 is a top plan view thereof; FIG. 6 is a fragmentary cross-sectional view thereof, taken in the plane represented by line 6—6 in FIG. 5; and, FIG. 7 is a bottom plan view thereof.
